UNITED STATES PATENT OFFICE

OTTO SEVERIN RUUD, OF OSLO, NORWAY

DEVICE FOR REGULATING THE SIZE OF THE COMBUSTION CHAMBER IN COMBUSTION MOTORS

Application filed July 12, 1928, Serial No. 292,181, and in Germany February 27, 1928.

In combustion motors having adjustable size of the combustion chamber it is proposed to adjust by means of wedges the size by an adjusting piston movable axially to the driving piston in the motor.

In such devices it has been difficult in motors having a plurality of cylinders to adjust the combustion chambers owing to the fact that the pressure of the combustion does not occur simultaneously.

The present invention relates to improvement in means by which the said difficulties are avoided and without complicating the construction of the motor.

15 The invention may also be used in motors of old construction as only the head of the motor casing need be renewed.

The invention contains no mechanism which should be manipulated and the 20 adjusting is caused by a suitable spring. Trials have demonstrated that it is superfluous to arrange a special adjustment of each cylinder and that it is advantageous to connect the several bottom pistons to each 25 other so that they are arranged to be adjusted simultaneously. Such adjustment is much more quiet and noiseless than in other systems.

According to a preferred construction the 30 bottom pistons are placed eccentrically to the combustion cylinders so that a very suitable feeding arrangement of the fuel is obtained. Levers are also arranged to transfer the pressure of the spring to the bottom pistons so 35 that a certain multiplication of the pressure is obtained.

In the accompanying drawings:

Fig. 1 is partly an elevation and partly a 40 section of a part of the head of a combustion motor according to the present invention.

Fig. 2 is a horizontal view of the same.

Fig. 3 is a sectional view upon the line III—III, Fig. 2.

In the drawings 1 designates a combustion 45 cylinder with piston 2. 3 designates the head of the motor casing and 4 the inlet channel for the fuel. Bottom cylinders 5 with bottom pistons 6 are placed alongside of the combustion chambers in the head. The 50 bottom pistons are each provided with a re-

cess 7 above a fuel channel controlled by a valve 8. In the lower position of the piston the valve only has a limited gas inlet chamber sufficient to a reduced operation of the motor and the valve in lifted position of the 55 piston, allows a free inlet of the gas. The piston 6 is pivoted to the piston rod 9 by means of a pivot 10. The piston rod 9 is in turn by means of the pivot 11 connected to the crank 12 of the shaft 13. The shaft 13 is supported by bearings 14. Two of the cranks are provided with projections 15 having a spherical recess in which a link 16 is supported. The upper part of the link is supported in a cup 17 which is acted upon by a spring 18. The spring 18 is kept in place by a holder 19. The complete device is enclosed in a cap 20 secured to the cover by wingscrews 21. 22 designates the sparking plugs which are placed in the front of the 60 lifted part of the head.

If the power of the motor is increased the combustion pressure is increased almost simultaneously for all cylinders. Owing to this fact the spring pressure is overcome and consequently the bottom-piston 6 is lifted and the crankshaft 13 turned. As the pressure of the spring has a greater momentum arm than the piston pressure a comparatively weak spring will suffice to cause the necessary 65 bottom piston pressure. The spring pressure is proportionate to the adjustment of the bottom piston. The increase of the compression chambers for the next compression consequently will correspond to the combustion pressure. When the yielding is reduced the bottom piston again is returned by means of the spring 18 to their original positions.

It will be understood that the shown construction is only an example and that the details may be varied in several manners without departing from the scope of invention as defined in the appended claims.

Claims:

1. In a multi-cylinder internal combustion engine, wherein the capacities of the compression chambers are variable by means of cylinder head pistons, the combination with means positively connecting together all the cylinder head pistons so as to cause them to

move up and down as a whole, of a loading device constantly acting upon said means to tend to push all pistons inwards and adapted, under the influence of the total sum of pressures in all cylinders, to yield to a degree depending upon the value of the said sum.

2. In a multi-cylinder internal combustion engine, wherein the capacities of the compression chambers are variable by means of cylinder-head pistons, the combination with means positively connecting together all the cylinder head pistons so as to cause them to move up and down as a whole of a spring device constantly acting upon said means to tend to push all pistons inwards and adapted, under the influence of the total sum of pressures in all cylinders, to yield to a degree depending upon the value of the said sum.

3. In a multi-cylinder internal combustion engine, wherein the capacities of the compression chambers are variable by means of cylinder head pistons, the combination with means positively connecting together all the cylinder head pistons so as to cause them to move up and down as a whole, of a freely yielding spring device constantly acting upon said means to tend to push all pistons inwards and adapted, under the influence of the total sum of pressures in all cylinders, to yield to a degree depending upon the value of the said sum.

4. In a multi-cylinder internal combustion engine, wherein the capacities of the compression chambers are variable by means of cylinder head pistons, the combination with said pistons of a common shaft, cranks rigidly connected with the shaft and adapted to exert inwardly directed pressure upon each piston and a spring device tending to rotate said crank shaft yieldingly in a direction so as to push all pistons inwardly to a degree depending on the total sum of pressures in all cylinders.

5. In a multi-cylinder internal combustion engine, wherein the capacities of the compression chambers are variable by means of cylinder head pistons, the combination with said pistons of a common shaft, cranks rigidly connected with the shaft and adapted to exert inwardly directed pressure upon each piston, a common leaf spring coacting with the cranks, links provided with spring supporting parts and acting to transfer the spring pressure to the pistons, whereby the whole system of spring loading members is adapted, under the influence of the total sum of pressures in all cylinders, to yield to a degree depending upon the value of the said sum, the said links being arranged at a greater distance from the crank shaft than the distance from the latter to the pivots of the piston rods.

6. In a multi-cylinder internal combustion engine, wherein the capacities of the compression chambers are variable by means of

cylinder head pistons, the combination with the adjustable cylinder head pistons of a common shaft, cranks on the shaft, piston rods connecting the said shafts to the said pistons, means for transferring a resilient pressure to the said cranks so as to push said pistons resiliently inwards and so as to allow all pistons, under the influence of the total sum of pressures in all cylinders, to yield inwardly to a degree depending upon the value of the said sum, driving pistons being arranged eccentrically to the axis of the cylinder head pistons, inlet valves arranged below the cylinder head pistons, and means for transferring fuel gases to the compression chambers enclosed between the driving pistons and the cylinder head pistons.

In testimony whereof I affix my signature.
